F. PARCELLI

CHIPPING TOOL

Filed June 9, 1923

Ferdinand Parcelli,
INVENTOR.

BY E. E. Overholt,
ATTORNEY.

UNITED STATES PATENT OFFICE.

FERDINAND PARCELLI, OF MOUNT KISCO, NEW YORK, ASSIGNOR OF ONE-HALF TO
FRANK PASQUALE, OF MOUNT KISCO, NEW YORK.

CHIPPING TOOL.

Application filed June 9, 1923. Serial No. 644,450.

To all whom it may concern:

Be it known that I, FERDINAND PARCELLI, a citizen of the United States, residing at Mount Kisco, in the county of Westchester, and State of New York, have invented certain new and useful Improvements in Chipping Tools, of which the following is a specification.

My invention relates to wood working tools, and more particularly to a chipping tool somewhat in the nature of an adz.

My object is to provide a device of this character adapted to give a much smoother and more even surface than an adz, and also adapted to work in places where it would be impossible to use an adz.

Another object is to provide a device of this character which can be conveniently manipulated with one hand.

A still further object is to provide a device in which the handle and cutter will be held in very rigid relation to each other, and yet can be easily separated, when desired, for grinding the cutter, whereby to make it easy to always keep the same in prime condition.

Minor objects will appear in the subjoined description.

The invention consists in the novel construction and arrangement of the parts, as will be hereinafter described and claimed, reference being had to the accompanying drawings, in which;—

Fig. 1 is a side elevation of the device ready for use.

Fig. 2 is a perspective view of the cutter with the handle removed.

Fig. 3 is a bottom plan view of the device; and,

Fig. 4 is a perspective view of the securing band which holds the cutter in binding engagement with the handle.

The numeral 1 indicates the handle of the device; 2 the cutter; and 3, the band which binds the handle and cutter together. The handle has a forwardly projecting convex portion 1^a provided in its upper edge with a notch 4 for engagement with the securing band 3; while the handle proper of the device is curved rearwardly and upwardly and then downwardly, and is indicated by 1^b.

The cutter 2 of the device has the broad portion 2^a which forms the cutter proper and is provided at its inner end with a chisel edge 5.

The integral, forwardly projecting portion 2^b of the cutter is of the same width as the thickness of the handle 1, and has a shoulder 6 at its inner end, which engages a cooperating shoulder 7 on the under side of the handle 1. The portion 2^b is also provided on its under side with a shoulder 8 spaced forwardly of the shoulder 6 on the upper side. This shoulder 8 forms an offset of a thickness equal to the thickness of the lower end section of the securing band 3, so that when the band is in operative position on the device, as illustrated in Fig. 1, said lower end of the securing band will be flush with the bottom of the inner end portion of the cutter, as indicated in Fig. 1.

I will now describe a portion of my device which may be either employed or omitted, at the option of the manufacturer, as the device will work either with or without it, as will be more fully understood when the operation of the device is described. The portion just referred to consists of a metallic plate 9, secured in any preferred way, as by screws 10, to the under side of the convex portion 1^a of the handle, and projects a little in advance of said handle portion, as indicated at 9^a. This projecting portion 9^a has a threaded opening 11, into which is received a screw 12 provided with a point 13 at its lower end, which point takes into the conical recess 14 in the forward end of the portion 2^b of the cutter.

The operation of the device is very simple. When it is desired to assemble the parts, the securing band 3 is first slipped over the forward-end portion 1^a of the handle and dropped into the notch 4. The reduced portion 2^b of the cutter is then slipped through the lower end of the band till the shoulder 8 engages the band, at which time also the shoulder 6 on the upper side of the cutter engages the cooperating shoulder 7 on the under side of the handle portion 1^a. The device is then ready for use, and the parts will have no tendency to separate from each other when in use, because the rearward pull of the handle 1^b as it forces the cutter to its work, always tends to force the parts into the relative positions just indicated. The portion 2^b of the cutter is slightly tapered at its sides at its extreme forward end, as indicated at 15, to cause it to easily enter the opening at the lower end of the securing band 3.

When the cutter is separated from the other parts, as illustrated in Fig. 2 of the drawings, it is as easily ground as a chisel or a plane bit; and under ordinary circumstances, the parts do not need to fit so tightly together as to make it difficult to remove the cutter for sharpening: however, in cases where it becomes necessary to use the device under circumstances where the handle becomes wet or charged with moisture, it might swell so tight that it would be difficult to remove the cutter. But with the adjusting plate 9 and the screw 12, it will be seen that the cutter can be made to slip easily into and out of the securing band 4, and yet by a slight downward turn or two of the screw 12 into the opening 14, the parts may be bound in very rigid engagement with each other, even though the handle should be unusually shrunken. Also it will be seen that the screw 12 taking into the conical opening 14, will lock the cutter against movement either forwardly or rearwardly relatively to the handle 1. In fact, this arrangement will permit the parts to all be fit easily together, and will yet insure them being absolutely rigid when in use.

Instead of the device being pulled to its work by the handle portion 1^b, it may be pushed to its work when desired with the palm of the operator's hand on the convex forward end 1^a of the handle.

Having now described my invention, what I claim as new and desire to protect by Letters Patent is:—

1. A device of the character described, comprising a cutter having an upper and a lower shoulder, with a reduced portion extending forwardly from the lower shoulder; a handle with a notch in its upper edge; and a securing band surrounding the handle

with its upper end received into said notch, and with its lower end projecting below the handle sufficiently to receive the reduced portion of the cutter, said reduced portion being passed through said downwardly projecting portion of the band with its under shoulder in engagement with the lower end of the band.

2. A device of the character described, comprising a cutter having an upper and a lower shoulder, with a reduced portion extending forwardly from the lower shoulder; a handle with a notch in its upper side; a securing band surrounding said handle with its upper end received into said notch, and having its lower end projecting below the handle, with the reduced portion of the cutter received into said projecting portion of the securing band; and adjustable means for placing tension on said band to lock the handle and cutter together.

3. A device of the character described, comprising a cutter having an upper and a lower shoulder, with a reduced portion extending forwardly from the lower shoulder; a handle having a convex forward portion provided with a notch on its upper side, and a rear portion curved upwardly and rearwardly and then downwardly to form a handle proper for manipulating the device; a securing band surrounding the handle and reduced portion of the cutter, with its upper end received into said notch and its lower end in engagement with the lower shoulder of the cutter, said handle also having a shoulder on its under side for cooperative engagement with the shoulder on the upper side of the cutter.

In testimony whereof I affix my signature.

FERDINAND PARCELLI.
